(57) **CLAIM**

The ornamental design for a ultrasonic flow meter, as shown and described.

DESCRIPTION

FIG. 1 is a left front perspective view of an ultrasonic flow meter according to the present invention.

FIG. 2 is a left rear perspective view thereof.

FIG. 3 is a right rear perspective view thereof.

FIG. 4 is a front view thereof.

FIG. 5 is a rear view thereof.

FIG. 6 is a left side view thereof.

FIG. 7 is a right side view thereof.

FIG. 8 is a top view thereof.

FIG. 9 is a bottom view thereof.

FIG. 10 is a left front perspective view of an alternative embodiment of an ultrasonic flow meter according to the present invention.

FIG. 11 is a left rear perspective view thereof.

FIG. 12 is a right rear perspective view thereof.

FIG. 13 is a front view thereof.

FIG. 14 is a rear view thereof.

FIG. 15 is a left side view thereof.

FIG. 16 is a right side view thereof;

FIG. 17 is a top view thereof; and,

FIG. 18 is a bottom view thereof.

1 Claim, 16 Drawing Sheets
